UNITED STATES PATENT OFFICE.

HERMANN HEINRICH EDUARD GEORG KOHL, OF LEIPSIC-REUDNITZ,
GERMANY.

PLATE-HOLDER FOR MECHANICAL PRINTING.

SPECIFICATION forming part of Letters Patent No. 426,283, dated April 22, 1890.

Application filed April 13, 1889. Serial No. 307,176. (No model.) Patented in Belgium April 30, 1889, No. 85,807; in France May 12, 1889, No. 136,752; in Italy July 30, 1889, XXIII, No. 25,332, and in Switzerland August 2, 1889, No. 837.

To all whom it may concern:

Be it known that I, HERMANN HEINRICH EDUARD GEORG KOHL, of Leipsic-Reudnitz, Germany, a citizen of Germany, have invented certain new and useful Improvements 5 in Photographic-Plate Holders, (for which I have received patents in France May 12, 1889, No. 136,752; in Italy, July 30, 1889, XXIII, No. 25,332; in Switzerland, August 2, 1889, No. 837; 10 in Belgium, April 30, 1889, No. 85,807,) of which the following is a specification.

For the purpose of producing printing-plates in lines or stipples from photographs or other objects in nature it is necessary to 15 divide the half-tones of the picture by means of a net-work of lines into a system of lines or dots. For this purpose a transparent or diaphanous plate provided with a system of lines is placed in front of the sensitive plate 20 into a plate-holder of the photographic camera and then the sensitized plate exposed, the plate-holder closed, and in the dark-chamber a second transparent or diaphanous plate provided with a system of parallel lines 25 placed in such a manner in front of the negative that the lines of the second plate cross the lines of the first plate at an angle of ninety degrees. The plate-holder is then again inserted into the apparatus and exposed again. 30 As the system of lines of the transparent or diaphanous plates are first horizontal and then vertical, or inclined in one direction and then inclined in another direction, or vice versa, they produce on the negative the corresponding system of cross-lines, without 35 which the negative would not be adapted for producing from the same printing-plates in relief. In the process described the changing of the line-plates is tedious and objectionable, especially as the position of the negative may be slightly changed, and thereby be doubled by exposures. These objections 40 are intended to be remedied by the plate-holder, which forms the subject-matter of this application and which consists of a rotary 45 line-plate which is attached to a ring that is guided in a grooved circular opening of the plate-holder, the said ring being moved with the line-plate through an angle of ninety degrees by means of a cord, as will be fully de-

scribed hereinafter, and finally pointed out in the claims.

In the accompanying drawings, Figures 1 and 3 represent front views of my improved plate-holder before and after shifting the 55 same. Fig. 2 is a horizontal section of the same on line *x x*; Fig. 1; and Fig. 4 is a detail horizontal section showing the clamping mechanism for the line-plate on a larger scale.

Similar letters of reference indicate corresponding parts.

Referring to the drawings, A represents the transparent or diaphanous plate, which is provided with a system of parallel lines in the usual well-known manner. The line-plate A 65 is supported in a circular metallic frame B, which is guided in a circular shouldered or grooved opening D of the plate-holder C of the photographic camera and retained therein by projecting lugs or clips E. The line-plate A 70 is supported in the circular frame B by grooved parallel strips G and H, of which the strip H is secured to the ring-frame B, while the strip G is connected by means of set-screws O with plates O', that are attached to the frame B, 75 as shown in Figs. 1, 3, and 4. A rotary motion through an angle of ninety degrees can be given to the frame B of the line-plate by means of a cord or gut string K, which is attached at the back and guided along the circular frame B and then conducted through a lateral hole T to the outside of the plate-holder. 80

n and *o* are fixed stops on the plate-holder, one at the upper part and the other at one side of the same. By pulling the cord K the 85 line-plate is turned ninety degrees until the pin P on the frame B abuts against the stop *o*.

The cord or gut string is retained on the frame B by means of a retaining-spring F, which holds the same in contact with the 90 circumference of the frame.

In using the apparatus it is only necessary to bring the line-plate A in its initial position, (shown in Fig. 1,) after which the sensitized plate is partly exposed. The cover is 95 then placed on the lens-tube of the camera and the line-plate turned by the cord K, so that it assumes its second position at right angles to the former position, as shown in Fig. 3. The cover is then removed and the 100

sensitized plate exposed again until it is completed. In this manner a system of lines is produced on the plate until the half-tones of the plates are dissolved into lines or stippling in the well-known manner.

Having thus described my invention, I claim as new and desire to secure by Letters Patent—

1. A plate-holder for photographic cameras, having a circular guide-opening, combined with a rotary circular frame guided in said opening, a line-plate supported in the rotary frame, and means, substantially as described, for turning the frame of the line-plate at an angle of ninety degrees, substantially as set forth.

2. The combination, with a plate-holder having a circular guide-opening, of a rotary frame guided in the said opening, a line-plate mounted in grooved strips of said rotary frame, set-screws for adjusting said strips, a string for rotating the frame of the line-plate, a pin on said movable frame, and stops for arresting the motion of the movable frame, substantially as set forth.

In testimony whereof I have signed my name to this specification in the presence of two subscribing witnesses.

HERMANN HEINRICH EDUARD GEORG KOHL.
